ANTISEPTIC ANIMAL APPLIANCE

Fritz Springborn and John E. Sinos,
Astoria, N. Y.

Application July 11, 1946, Serial No. 682,797

1 Claim. (Cl. 119—85)

1

The present invention relates to an antiseptic animal appliance and it particularly relates to a hair treating and disinfecting device, which although particularly applicable to animals, also has application to humans.

It is among the objects of the present invention to provide an appliance for applying antiseptic, germicidal or disinfectant material in desired small quantities to the hair and particularly to the hair of dogs with assurance of uniform distribution of the same on the hair and on the skin of the animal with a maximum of convenience and minimum of annoyance to the applicator or the animal.

Still further objects and advantages will appear in the more detailed description set forth below, it being understood, however, that this more detailed description is given by way of illustration and explanation only and not by way of limitation, since various changes therein may be made by those skilled in the art without departing from the scope and spirit of the present invention.

A particular feature of the present invention resides in the combination of a container, particularly suited for receiving germicidal, disinfectant or antiseptic powders which will serve as a handle for a comb or brush or combination comb and brush. The container is so constructed that upon each stroke of the comb or brush, a small amount of the powdered material will be deposited upon the hair of the animal in advance of the comb or brush. The stroke of the comb or brush then will effectively distribute such powder throughout the hair and upon the skin or scalp.

In the drawings which show several embodiments of the invention by way of illustration and not by way of limitation,

Fig. 1 is a top perspective view of a combination dispensing can and comb pursuant to the present invention,

Fig. 2 is a transverse sectional view upon the line 2—2 of Fig. 1.

Fig. 3 is a top perspective view of a top perspective view similar to Fig. 1 of an alternative embodiment with a curved comb.

Fig. 4 is a top perspective view of still another embodiment with a brush,

Fig. 5 is a fragmentary side sectional view of an alternative embodiment showing the comb directly soldered to the container.

Referring to Figs. 1 and 2, the container or can A has a cover B and carries the comb C by the clip D.

2

The container or can A is shown as a flat cylinder with a frustro-conical top, but it may be made of rectangular, ovoidal or even of partly annular shape to conform to the shape of the animal's or dog's body.

As shown the bottom of can A has a base 10 and a cylindrical side wall 11 with an intermediate ridge 12. The cylindrical side wall 13 of the lid or cover B telescopes onto the upper part 14 of the can wall 11 resting upon the ridge 12.

Fastened by the annular ring 15 to the curved edge 16 of the cover B is the annular frustro-conical diaphragm 17 of the cover B.

15 The center part of the diaphragm 17 is clamped between the plate 18 and the base of the inverted cup 19, the tongues 20 of the cup being struck up and bent over the disk or plate 18. The cup 19 receives the upper end 21 of the coil 20 spring 22. The lower end 23 of the spring 22 is grasped by the turned over portion 23 of the arm 24 so that the spring 22 is also attached to the cover assembly.

The bottom 10 of the container A has soldered 25 to it a clip D which receives the removable metal or plastic comb C. The sides 26 of the U-shaped cross section clip D tightly grips the top 27 of the comb C.

The side wall 11 of the container A adjacent 30 to and just above the comb C is provided with a plurality of openings or perforations 28 which release the powdered germicidal or medicinal material.

In operation, when the container A is grasped 35 preparatory to a stroke, the diaphragm 17 will be depressed forcing out a small amount of powder through the openings 28. Then the stroke will distribute and assure satisfactory distribution of the medicament, such as flea powder, 40 skin treating material or other powdered agent. All this is done with one hand without touching the dog's hair.

In the embodiment of Fig. 3, similarly functioning parts being indicated by the same letters and numerals as in Figs. 1 and 2, but primed, 45 the comb C' is curved to fit the back of a dog, and the clip D' has an extension 31 from the bottom 10' of the can A'.

In the embodiment of Fig. 4, similarly functioning parts being indicated by the same letters and numerals as in Figs. 1 and 2, however, provided with a superior 2. The brush C² is held by the clip D² extending from the bottom 10² of the can A².

55 In the embodiment of Fig. 5, similarly func-

tioning parts being indicated by the same letters and numerals as in Figs. 1 and 2 provided with a superior 3. The comb C³ is directly soldered or welded at 33 to the bottom 10³ of the can A³.

It is thus apparent that there is provided a compact, simple, durable antiseptic or medicating comb and/or brush for use on dogs or other animals which will enable ready treatment without touching the dog's hair or skin.

As many changes could be made in the above 10 antiseptic animal appliance and many widely different embodiments of this invention could be made without departing from the scope of the claim, it is intended that all matter contained in the above description or shown in the accompanying drawings shall be interpreted as illustrative and not in a limiting sense.

What is claimed is:

A combined animal comb and insecticide powder dispenser comprising a removable cover-cylindrical can with two sides and a cylindrical wall, said can serving as a handle for the dispenser and said can being provided with a diaphragm at one side in said cover, the bottom of said can at one side thereof being provided with 20 a U-shaped clip, a comb mounted within said clip flatly on the bottom of said can, the teeth

of which project away from said cylindrical wall of the can and lie in a plane perpendicular to the axis of the cylindrical can, said can having a plurality of openings in its cylindrical wall adjacent to the back of said comb and a return spring to return the diaphragm when pressed downwardly by the hand on grasping the can to eject the insecticide powder onto said comb during the combing operation.
